EMERGENCY RELEASE OF POWER-DRIVE DRAWER

Jack E. Martens, Gary, Ind., assignor to The Anderson Company, a corporation of Indiana

Filed Oct. 20, 1958, Ser. No. 768,329

9 Claims. (Cl. 74—424.8)

This invention relates to a motion-transmitting device and more particularly with such a device having a release mechanism for disengaging the device.

This invention pertains to a power-driven mechanism for shifting a carriage, such as an automobile seat or window, truck tailboard, garage door, machine table or the like. For the purpose of illustration the invention is shown as used for sliding to an accessible position, and retracting, a drawer or tray of a frozen-food locker or refrigerator.

The primary object of the invention is to provide an arrangement by which, in the event of power failure or mechanical difficulty, the drawer or other device may be readily opened or closed manually, without material hindrance from said mechanism.

According to the forms of the invention shown, a drawer or carriage is shifted by means of a threaded shaft, one end of the shaft being connected to exert a push or pull upon the drawer. Readily releasable means is provided for normally latching the shaft against rotation. A motor-driven antifriction motion-transmitting nut assembly is threaded upon said shaft, while held against travel therealong, thus causing the shaft to move along its axis when the nut assembly is driven. For accomplishing the object indicated, nut assemblies available under the trademark Roton, a product of The Anderson Company, Gary, Indiana, present the peculiarly desirable quality of extremely low frictional drag. If either the shaft or the Roton-type nut is free to turn, as by releasing the latch above mentioned, then manually pushing upon the handle of the drawer will readily pass the shaft through the Roton-type nut, substantially untrammelled.

Additional objects and attributes of the invention will become evident when the description hereinafter set forth is considered in conjunction with the drawings annexed hereto.

In the drawings:

Figure 1 is a side view showing the application of the invention to a drawer of a food locker or refrigerator, portion of the latter being shown in section;

Figure 2 is an enlarged view taken on line 2—2 of Figure 3 showing in detail the shaft and motion-transmitting nut arrangement;

Figure 3 is a front view showing the motor drive connection to the motion-transmitting nut, and one means of locking the threaded shaft against rotation;

Figure 4 is a detail of the shaft locking device of Figure 3, showing the manner in which the shaft applies thrust to the drawer;

Figure 5 is a view corresponding to Figure 2, but illustrating a modification of the means for restraining the shaft against rotation;

Figure 6 is a detail view of the restraining means of Figure 5, in opened or released position; and

Figure 7 is a view taken on line 7—7 of Figure 5, looking in the direction of the arrows.

Referring more particularly to the drawings, wherein similar reference numerals refer to similar parts throughout the several views, and specifically referring to Figures 1—4, 10 designates a portion of a locker or refrigerator casing, supported upon a framework 12, and 13 is

2

a drawer mounted in an opening formed in the casing, to be slid or rolled outward, as shown in dotted lines, to a position where its contents are accessible, and thereafter returned to its normal storage position within the casing. Drawer 13 includes a front wall 14 somewhat larger than the opening for the drawer, and this front end wall is provided with a handle 15. The usual combined seal and insulation material 16 is provided for engaging the periphery of the front wall 14 of the drawer.

10 The framework 12 is designed to provide space for the power-operated mechanism which is normally to advance and retract drawer 13. This mechanism includes a threaded shaft 17, and a power-driven antifriction nut assembly 18 engaging the threads of said shaft, the nut assembly being restrained from moving axially of the shaft. One end 19 of the shaft 17 is connected to a bracket 20, which bracket in turn is secured by screws 21 to the lower edge of the front 14 of the drawer 13. A releasable latch device 22, carried by bracket 20, normally restrains shaft 17 against rotation. Thus, upon rotation of the nut assembly 18, shaft 17 will be moved axially to advance or retract the drawer.

15 Nut assembly 18 is mounted for rotation in an anti-friction bearing 23, the outer elongate ring member 24 of the nut assembly being fixed to the inner race 25 of bearing 23 to prevent axial movement of the nut assembly. The outer race 26 of the bearing is supported from frame 12 by a pair of arcuate clamp arms 27, partially encircling the outer race (Figure 3). Each 20 clamp arm 27 in turn is attached to frame 12 by bolt means 28.

25 A pulley 29 is secured to an extension 30 of ring element 24 of the nut assembly. The pulley 29 is driven from reversible electric motor 31, also mounted on frame 12, through belt 32. It is manifest that motor 31 is to be controlled from suitably placed switch means, not shown.

30 As alluded to above, the inverted U-shaped bracket 20 is secured to the drawer and has an opening 33' in the inner leg 33 through which the end portion 19 of shaft 17 extends. The end 34 of shaft 17 is shown as pointed to reduce friction with the point abutting the outer leg 35 of bracket 20. A pin 36 passes through and is fixed in an opening provided in the end portion 40 19 of shaft 17 with the overhanging end portions of the pin engaging the inner face of the latch device 22, which in turn bears against the inner wall of leg 33 of bracket 20.

45 Latch device 22 is shown as a plate slidably mounted on leg 33 of bracket 20 by means of a headed shoulder pin 37, which pin passes through slot 38 formed in the latch and is threaded or riveted for engagement with leg 33 of the bracket. Abutments 39 are provided near one 50 end of plate 22 adapted to be brought into engagement with the end portions of pin 36 to lock shaft 17 against rotation. The opposite end of plate 22 is formed with a ledge or finger grip 40 to facilitate sliding plate 22 into and out of locking relation with respect to pin 36 of shaft 17.

55 60 A tubular protective member 41 extends over and along shaft 17. The ends of member 41 are rigidly supported on the locker casing 10 by means of support brackets 42. The free end of shaft 17 is provided with an abutment 43, and a corresponding abutment 44 is secured to shaft 17 near its opposite end, beyond the nut assembly 18. These abutments are designed to engage cage member 45 of the nut 18 and stop the thrust of shaft 17 on the drawer, as will appear hereinafter. Abutment 43 is provided with a raised bearing portion 46 engaging the inner wall of tubular member 41 to steady the free end of shaft 17, while permitting both rotary and axial movement of shaft 17 within said member 41.

65 70

A nut assembly of the type disclosed by U.S. Patent No. 2,714,005, or variants thereof, available under the trademark Roton is peculiarly useful in the present organization. The form of Roton-type nut shown in Figure 2, as mentioned above, includes a tubular ring element 24, secured to the inner race 25 of bearing 23 to restrain said element against axial movement. The interior of element 24 is formed with an intermediate portion 47 of reduced internal diameter, providing a pair of oppositely facing raceways or abutments therein, facing the opposite enlarged ends 48 of ring element 24.

A plurality of bearing elements 49 are interposed between the threads of shaft member 17 and raceways 47 of ring member 24 to adapt these members for relative rotational and endwise movement and to transfer or transmit the motion and load or force from one member to the other. The bearing elements 49 are preferably of the type wherein at least two generally toroidal bearing surfaces are axially spaced a distance corresponding to the width of portion 47 of member 24, so that the bearing surfaces of elements 49 are positioned in contact with the raceways formed by portion 47. Loosely positioned about the threaded shaft 17, within the ring 24, is the tubular cage member or carrier 45, which has openings within which are nested the bearing elements 49.

Rotation of nut assembly 18 in either direction rotates the bearing elements 49 about their own axes and also planetates them about the axis of the shaft 17. The planetation causes the bearing elements 49 to roll up or down the spiral surfaces of shaft 17 depending upon the direction of rotation of motor 40. Since the nut assembly 18 is not permitted to move along the shaft 17, and the shaft is normally locked against rotation, the rotary action of nut assembly 18 imparts an axial movement to shaft 17.

It should be understood that, when either abutment 43 or 44 of shaft 17 engages cage 45 of the nut assembly, planetation will cease and ring 24 will idly spin upon bearing elements 49, without effecting material thrust on shaft 17. By disposing the abutments 43 and 44 at positions corresponding to limits of travel desired for drawer 13, opening or closing movement of the drawer will stop at such set positions, even though motor 30 continues to run. It is clear, therefore, that the arrangement disclosed avoids the use of motor controls which otherwise would be necessary to prevent strain and jamming of the apparatus.

By reason of the extremely low frictional characteristics and other features of design of nut assembly 18, should either the nut assembly or the shaft 17 be free to rotate, then shaft 17 may be readily moved through the nut assembly in either direction. Thus, in case of power failure or mechanical difficulty, by simply sliding latch 22 to the right (Figure 3) to release shaft 17 for rotation, the drawer may be opened or closed untrammelled by the power-operated mechanism. This is particularly useful in the event the power fails with the drawer open, whereupon to close the drawer the latch 22 is released and pressure is applied to the drawer so that a force is exerted between leg 33 and the pointed end 24 of the shaft 17 such that the shaft will rotate freely about its axis through the nut 18 until the drawer is closed. Opening the drawer with the power off is extremely easy since the pin 36 passes through the opening 33' in the leg 33 of the bracket 20 of the drawer. The drawer is completely free of the shaft 17 and nut 18 as the drawer is opened.

In the modification of Figures 5-7, parts identical with those of the first form of the invention are designated by the same reference characters. A nut assembly 50 is shown mounted in a sleeve 51, which sleeve is snugly fitted into an opening in holder 52. Holder 52 in turn is supported on frame 12 by a metal stamping 53, which stamping is bolted to frame 12 by vibration-damping spacer bolts 54. As shown, holder 52 is attached to

stamping 53 by screws 55, or in any other conventional manner. A portion of stamping 53 diametrically opposite clamping bolt 54 is formed with an extension 56 received in a rubber block 57, secured to the locker or refrigerator casing 10 by metal holder 58. It will be observed that stamping 53 is formed with a central sleeve portion 59 in which an end of tubular member 41 is received and sustained. Further, stamping 53 prevents the nut assembly 50 from moving toward the left (Figure 5), while movement in the opposite direction is restrained by engagement of flange 60 of ring 24 with sleeve 51.

Pulley 62, in this modification, has been given a cup shape to effect compactness and to apply the radial load of the belt 32 centrally of ring 24.

The latch and thrust connections of shaft 17 to drawer 13 include an L-shaped bracket 64, having one leg 65 attached by screw 66 to front wall 14 of the drawer. Latch 67, for securing shaft 17 against rotation and transmitting its thrust to drawer 14, is carried by the depending portion 65 of the bracket. Latch 67 consists of a U-shaped spring having the ends 68 of each of its legs 69 inwardly and reversely curved into a substantially semi-circular shape. The bight 70 of the latch spring 67 is secured to bracket 65 by a pair of vibration-damping connectors 71. Shaft 17 is formed adjacent its pointed end 24 with a tapered circumferential groove 72 adapted to receive the inturned ends 68 of the legs 69 of spring 67.

A combined clamp and thrust plate 74 extends through and beyond matching openings 75 formed in legs 69 of spring latch 67. One end of plate 74 is formed with lugs 76 to prevent the plate 74 from being drawn entirely through leg 69, while the other end of plate 74 is provided with a cam arm 77, having a finger grip 78. Cam arm 77 has two cam surfaces 79 and 80 which are located different distances away from the center of the pivot 81 between the cam arm 77 and the plate 74. The cam surface 79 is located a greater distance from the center of the pivot 81 and, when in engagement with the lower leg 69 of latch 67, holds the lugs 76 on the plate 74 into engagement with the other leg 69 of the latch 67 to lock the ends 68 of the latch into operative engagement with the groove 72 on the end 24 of the shaft 17. Rotation of the cam arm 77 about the pivot 81 serves to release the ends 68 of spring legs 69 from engagement with the shoulder of groove 72 of shaft 17, at once releasing shaft 17 for rotation so that it becomes a simple matter to close the drawer when shaft 17 rotates freely in the nut 50. The central portion of plate 74 is formed with a recess 82 to receive the pointed end 24 of shaft 17 so as to reduce to a minimum the friction between the shaft 17 and the plate 74.

The combined shaft-to-bracket thrust connection and latch of Figures 5-7, aside from its simplicity, presents the highly desirable feature that the drawer 13 may be disconnected from shaft 17 in toto when the power fails with the drawer closed. Thus, in the event that power failure occurs when drawer 13 is closed, then, by operating cam arm 71 and releasing the shaft 17 from restraint, the power means is completely divorced from the drawer. The drawer can now be manually opened and closed as though there were no operating mechanism employed in the apparatus. Should the power failure occur while the drawer is open, the cam arm 77 is moved to the disengaged position and the drawer is closed by pushing thereon. The result is that the screw 17 rotates about its axis and spins right through the nut assembly. The drawer when disconnected from the shaft will operate in the manual phase, both in opening and in closing, entirely independent of the power mechanism.

Having thus described my invention, it is obvious that various modifications may be made in the same without departing from the spirit of the invention; and, therefore,

I do not wish to be understood as limiting myself to the exact forms, constructions, arrangements and combinations of parts herein shown and described.

I claim:

1. Power mechanism for operating a reciprocably mounted carriage comprising driving and driven units, one of said units being a threaded shaft, the other unit being a motion-transmitting nut assembly cooperating with said shaft, one of said units being operatively connected with the carriage to move therewith and to move the carriage axially of said units, the other unit being fixed against axial movement, power means for driving one of said units, and manually operable readily releasable means normally preventing rotation of the other unit with respect to said carriage.

2. Mechanism for operating a carriage back and forth comprising a threaded shaft, an antifriction nut assembly cooperating with the threads of said shaft, said assembly being fixed against movement along said shaft, said assembly comprising a ring having races formed therein spaced according to the threads of said shaft, bearing elements each having spaced thread and race engaging portions, a tubular cage within said ring and having apertures receiving said bearing elements, one end of said shaft being connected with said carriage to move the same in either direction, means releasably latching said shaft against rotation, and reversible power means for rotating said nut assembly.

3. A closure operator comprising a threaded shaft having one end connected to said closure to apply a force thereto, an antifriction nut assembly threadedly engaging said shaft, means mounting said nut assembly for rotation while restraining the assembly against movement axially of said shaft, the nut assembly substantially supporting said shaft, a tubular member mounted to receive the free end of said shaft, abutment means fixed to said shaft on either side of said nut assembly, the abutment within said tubular member including a head engaging said tubular member to steady the free end of said shaft, a reversible motor operatively connected to rotate said nut assembly, and releasable means for latching said shaft against rotation.

4. Means for operating a carriage comprising a frame, an antifriction nut assembly rotatably mounted on said frame while restrained from axial movement, reversible motor means operatively connected to a member of said nut assembly to rotate the same, a threaded shaft extending through said assembly in threaded engagement therewith and supported thereby, plate means rigid with said carriage, one end of said shaft being provided with means connected to said plate means to exert a push or pull on said carriage depending upon the direction of rotation of said nut assembly, and releasable latch means normally locking said shaft against rotation.

5. Means for operating a carriage, comprising a support, a nut assembly rotatably mounted on said support while restrained from axial movement, reversible power means operatively connected to a member of said nut assembly to rotate the same, a threaded shaft extending through said nut assembly in threaded engagement therewith and supported thereby, a U-shaped bracket rigid with said carriage, one end of said shaft being pointed and engaging one leg of said bracket for operative contact when the shaft and carriage are moved in one direction, abutment means carried by the shaft and engaging the other leg of said bracket for operative contact when the shaft and carriage are moved in the opposite direction, and releasable latch means mounted on the bracket, engageable with means on the shaft to prevent rotation of the latter.

6. A carriage-actuating mechanism, comprising a frame, an antifriction nut assembly rotatably mounted on said frame while restrained against axial movement, reversible power means for rotating one member of said assembly, a threaded shaft passing through and supported by said assembly in threaded engagement therewith, one

end of said shaft being formed with a pointed end and a circumferential groove adjacent the pointed end for operative connection with said carriage to advance or retract the same, said connection comprising a U-shaped spring clip secured at its bight to said carriage, the free ends of the legs of said clip being formed with inturned tips for engagement in the groove of said shaft, and manipulatable means bridging said legs for bringing said tips into clamping engagement in said groove, said last-named means including a recessed portion for abutting the pointed end of said shaft.

5 7. Carriage-actuator mechanism comprising a support, a nut assembly comprising an elongate ring member formed with spaced raceways on its inner wall, bearing elements, each element having spaced toroidal portions operating in said raceways, a tubular cage within said ring having openings receiving said bearing elements, means rotatably mounting said ring on said support while restrained from axial movement, reversible power means 15 operatively connected to the ring of said nut assembly to rotate the same, a threaded shaft extending through said nut assembly in threaded engagement with said bearing elements, means connecting one end of said shaft to said carriage for exerting push or pull thrust upon said 20 carriage as the output of the motor is rotated in one direction or the other, releasable latch means for locking the shaft against rotation, a tubular housing mounted to receive the free end of said shaft, and an abutment secured to said shaft near each end thereof and on opposite sides 25 of said nut assembly, the abutment within said tubular housing being in sliding contact therewith to steady said shaft.

30 8. Power-operated mechanism for moving a carriage back and forth comprising a framework, means mounting an antifriction nut assembly on said framework, said means including a dished metal stamping, vibration-damping means connecting peripheral portions of said stamping to said framework, the central portion of said stamping being formed with an opening and a flange portion 35 extending outwardly from said opening, a holder secured to said stamping, said holder having an opening therethrough aligned with said flange, a sleeve fitted in the opening of said holder, said sleeve having a flange abutting said holder to limit its movement in one direction while engaging said stamping to limit its movement in the opposite direction, an antifriction nut assembly including an outer ring disposed in said sleeve, said ring having a flange engaging said sleeve to limit its movement in one direction while restrained by said stamping 45 40 50 55 60 65

in the opposite direction, a threaded shaft passing through said nut assembly, one end of said shaft being rotatably connected to said carriage, a tubular housing receiving the opposite end of said shaft, said housing being mounted in said flange of said stamping, power means for rotating the nut assembly, and readily releasable means for locking said shaft against rotation.

9. Mechanism for operating a reciprocable carriage or the like comprising a reciprocable shaft operatively connected with said carriage, power-driven nut means drivably connected to said shaft for moving said shaft and carriage, and readily releasable latch means connecting said shaft and carriage against relative axial and rotational movement, whereby release of said latch means permits the carriage to be manually moved relative to said shaft.
